[57] CLAIM

The ornamental design for a stenographic ruler, as shown and described.

DESCRIPTION

FIG. 1 is a top plan view of a stenographic ruler showing our new design;

FIG. 2 is a bottom plan view thereof;

FIG. 3 is a typical edge elevational view thereof;

FIG. 4 is a typical end elevational view thereof;
 FIG. 5 is an enlarged, fragmentary view of the left end of FIG. 1;

FIG. 6 is an enlarged, fragmentary view of the left end of FIG. 2.

The dashed lines of FIGS. 1 and 2 indicate that the numerals continue the length of the ruler.
